UNITED STATES PATENT OFFICE.

FRANK E. PETERS, OF INDIANAPOLIS, INDIANA.

BUILDING WALL.

Application filed March 17, 1925. Serial No. 16,225.

My said invention relates to concrete structures and it is an object thereof to provide an improved tile or building block made of semi-wet concrete.

- 5 A further object of my invention is to provide a monolithic wall or analogous structure composed of such tiles laid in courses and permanently united, either with or without reenforcing material.
- 10 Another object of the invention is to provide such a wall with dead air spaces and with live air spaces for circulation of air through the wall, the dead air spaces serving for absorption of moisture which might be detrimental to the wall or other structure and the live air spaces serving to maintain a uniform temperature throughout the entire structure, as well as to absorb moisture and carry it out of the structure.
- 15 A further object of the invention is to provide a wall structure of such a nature that the finishing coat of stucco on the outer face of the wall or the white or sand finish coat on the inner face can be applied directly 20 to the tile wall without the necessity of an intermediate or brown coat by reason of the uniform color and the porous nature of the wall.

Referring to the accompanying drawings which are made a part hereof and on which similar reference characters indicate similar parts,

- Figure 1 is a perspective of my improved tile,
- 35 Figure 2, a section on line 2—2 of Figure 1,
- Figure 3, a section on line 3—3 of Figure 1,
- 40 Figure 4, a section on line 4—4 of Figure 1,
- Figure 5, a perspective of a part of a wall or other structure illustrating the use of my improved tile, and
- 45 Figure 6, a section on line 6—6 of Figure 5.

In the drawings reference character 10 indicates my improved tile which has parallel longitudinal channels 11 near the outer edges of the upper face and parallel channels 12 spaced inwardly from the first-named channels. The channels 11 are so positioned as to receive spaced projections 13 on the under face of a superposed tile, which projections are spaced apart so as to occupy about half the length of the channel and may be slightly narrower than the width

of the channel, but preferably fit rather closely therein. By this construction it is possible to deposit mortar in the channels 11 in the laying of a wall or other structure which mortar will not be visible from either face of the wall and thus constitutes a secret joint between the successive courses of tiles. The mortar constitutes means for leaving up the courses of tiles to keep the top of the wall exactly level.

The channels 12 remain open and as shown in Fig. 6 are semi-circular in section, complementary channels being formed in the lower face of a superposed tile to form a circular passage extending horizontally throughout the structure thus forming horizontal air passages which may extend completely about the structure if in the form of a fence or building and which may be open at the ends if the ends are exposed or may be closed by a finishing coat covering the structure. The channels 12 are intersected by vertical channels 14 in the respective tiles which channels register wholly or in part with those of the tiles above and below so as to form air passages extending from top to bottom of the structure and this intersection with the horizontal passages insures uniform temperature throughout the structure. It has been found that one tenth of a degree of difference in temperature of air at different places will cause it to travel. Assuming that one side of a building structure according to my invention is warmer than the other the heated air in the air passages would rise and cold air would be drawn from the opposite side of the building whereupon a circulation would be established, the heated air passing through the upper part of the walls toward the colder side of the building and vice versa, drawing the air from the colder side of the building toward the warmer to keep the walls from expanding.

Dead air pockets are illustrated at 15, these pockets being located between the projections 13 and opening on the lower face of the tile. The tile is made of semi-wet concrete so as to be porous when completed. These ports, of course, are filled with air and connect the dead and the live air spaces so as to absorb the moisture which otherwise might be detrimental to the structure. A wide semi-circular central channel is provided on each face of the tile at 16 and it will be obvious that these channels register in super-

posed tiles to form a horizontal channel approximately circular in section. The channels 16 are intersected by vertical channels 17 which are also circular in section.

- 5 When a sufficient suction of a structure has been laid the channels 16 and 17 are filled with wet concrete mortar which after hardening forms puddle concrete causing the tile of the entire structure to interlock 10 and form a monolithic building or other structure. It will be understood that the channels 17 register with one another from top to bottom of a wall so as to form pilasters 18 at intervals of about four inches from 15 center to center of the channels, connected by cylindrical horizontal bars 19. The horizontal channels may be reenforced with steel rods 20 as for making a reenforced concrete lintel. The vertical pilasters may also be 20 reenforced as indicated at 21. The keys or projections 18 fit with sufficient closeness in the channels 11 to insure that the wall will be substantially plumb from top to bottom. As above stated mortar may be used in each 25 of the channels 11 to level the wall as it is being constructed but preferably such mortar will be used only in the last row of a scaffold height, this being generally all that is necessary.
- 30 Vertical grooves 22 are formed at the ends of the tile, these grooves forming auxiliary dead air pockets.

In a structure such as illustrated in Fig. 5, which may be part of the wall of a house an 35 inside white coat or sand finish coat may be applied directly to the tile walls as according to my construction they have a surface of uniform color and therefore do not require the ordinary brown coat which is applied before the scratch coat. A coat of 40 stucco 24 may likewise be applied directly to the tiles at the outer side of the wall. When the finishing coats are being applied the pores in the tile form a suction and cause the 45 finishing coats to adhere so closely that they can not be separated from the tile after drying. The outside coat is usually made of water-proof material, but this is a matter of choice.

50 It will be obvious to those skilled in the art that various changes may be made in my device without departing from the spirit of the invention and therefore I do not limit myself to what is shown in the drawings and 55 described in the specification but only as indicated in the appended claims.

The reason for using a porous concrete tile 60 may be stated thus: the semi-wet concrete always makes a porous tile and when stucco or inside plaster is applied to such porous tile the moisture is drawn through the pores, and evaporated by the air in the pores which forms a suction and causes the coating to become imbedded or virtually causes it to be- 65 come a part of the tile.

By reason of the connecting horizontal and vertical channels or passageways an air circulation is provided throughout the wall and entirely around the building, thus providing for the maintenance of a substantially uniform or even temperature in all parts of the wall which keeps the walls from undue expansion and contraction due to variation in temperature. By this arrangement the air, being heated to one-tenth ($\frac{1}{10}$) of a degree in one location will start the air circulating, pulling the cold air from other parts of the wall or the opposite sides of the building, and even in the basement or below ground the temperature of the wall will be substantially uniform with other parts, and will vary not more than from fifteen (15) to twenty (20) degrees between winter and summer. This is an important feature in the durability and usefulness of the structure.

Having thus fully described my said invention, what I claim as new and desire to secure by Letters Patent, is:

1. A tile comprising a body having parallel horizontal channels in one face and a less number of correspondingly arranged projections on its opposite face, said projections being adapted to enter channels on another similar tile and being provided with pockets extending thereinto adapted to provide dead air cells when the tile is laid with other tiles of like conformation with the projections disposed in channels to form a structure, substantially as set forth.

2. A tile comprising a body having a channel in one face and a correspondingly arranged projection on its opposite face, said channel and projection being adapted to cooperate to hold the tile in position when laid with other tiles of like form, correspondingly arranged channels, one in each face of said tile, a passage connecting said channels through said tile and another passage extending into said tile from said projection, substantially as set forth.

3. In a concrete structure, courses of tiles each tile having parallel horizontal channels in one face and a complementary spaced projection on its opposite face entering such channels in a contiguous tile, the outer faces of the adjoining tiles being in contact while the opposed channels in the adjoining tiles disposed inwardly from the surface of the tile provide a secret mortar joint between adjoining courses of tiles, pockets extending into said tiles from said projections, said pockets being closed and providing dead air cells when the projections enter the channels of other tiles, substantially as set forth.

4. In a concrete structure, courses of tiles each having parallel spaced horizontal channels in one face and spaced horizontal projections on its opposite face in comple-

mentary relation, said channels and projections respectively receiving and extending into the projections and channels of the contiguous faces of adjoining tiles, the opposed channels in the contiguous faces of adjoining tiles forming a recess or secret mortar joint, central air channels on opposite faces of the tile parallel to the first named channels and registering vertical air passages connecting said central air channels, substantially as set forth.

5. A tile comprising a body having a groove about the same intermediate its extremities, said groove being adapted to provide an annular passage about the tile when laid with other tiles of similar form to provide means for locking the tile in the structure, said tile having a channel on one face at each side of said groove and a projection

at each side of said groove on the opposite face of said tile, recesses formed in said projections and adapted to provide a dead air space when the tile is laid with other blocks to form the structure, opposed grooves on opposite faces of said tiles and at each side of said first mentioned groove and passages connecting said groove, whereby when the tile is in position in a concrete structure with other tiles of like form the said grooves will align and form secret mortar joints and the passages align to form ventilating air channels, substantially as set forth.

In witness whereof, I have hereunto set my hand and seal at Indianapolis, Indiana, this 27th day of February, A. D. nineteen hundred and twenty-five.

FRANK E. PETERS. [L. s.]
